UNITED STATES PATENT OFFICE.

JOHN LOCKHART, OF TARRYTOWN, NEW YORK.

WINDOW-SHUTTER.

1,076,687.

Specification of Letters Patent.

Patented Oct. 21, 1913.

Application filed February 1, 1912. Serial No. 674,742.

To all whom it may concern:

Be it known that I, JOHN LOCKHART, a citizen of the United States, and residing at Tarrytown, in the county of Westchester 5 and State of New York, have invented certain new and useful Improvements in Window-Shutters, of which the following is a specification, such as will enable those skilled in the art to which it appertains to make 10 and use the same.

This invention relates to window shutters, and the object thereof is to provide shutters of this class which may be used as ordinary shutters, or partly as shutters, and 15 partly as window shades or awnings the lower portions of the shutters being hinged to the upper portions thereof, and being adapted to swing outwardly in planes at right angles to the window or the walls of 20 the building in which the windows are placed; and with these and other objects in view, the invention consists in devices of the class specified and constructed as herein-after described and claimed.

25 The invention is fully disclosed in the following specification of which the accompanying drawing forms a part, in which the separate parts of my invention are designated by suitable reference characters, and 30 in which:

Figure 1. an outside view of a window provided with shutters made according to my invention, and showing the shutters closed. Fig. 2. an inside view thereof. Fig. 35 3. a side view showing part of the window frame in section and the bottom part of a shutter swung outwardly on the hinges by which it is connected with the top part thereof. Fig. 4. a section on the line 4—4 40 of Fig. 1. Fig. 5. a section on the line 5—5 of Fig. 1. Fig. 6. a section on the line 6—6 of Fig. 1. Fig. 7. a section on the line 7—7 of Fig. 2, and Fig. 8. a section on the line 8—8 of Fig. 1.

45 In the drawing forming part of this specification I have shown a window frame comprising, side portions *a*, a top portion *a*² and a bottom portion *a*³, and in the practice of my invention I provide shutters comprising, top members *b* and bottom members *b*², and the top members *b* of the shutters are hinged to the sides of the window frame as 50 shown at *c*, while the bottom members of the shutter are hinged to the top members as shown at *c*². The lower end portions of the bottom members of the shutters are also

hinged to the sides of the window frame as shown at *d*, the hinges used for this purpose comprising parts *d*² secured to the window frame, and parts *d*³ secured to the shutters, and the parts *d*² which are secured to the window frame are provided, as shown in Figs. 1 and 8, with projecting spring jaw members *d*⁴ which open outwardly, and the parts *d*³ which are secured to the shutters 60 are provided with downwardly directed pinnacles *d*⁵ adapted to pass between said jaw members and held therebetween by friction, and to rotate therein.

The tops of the bottom shutter members *b*² are provided on their inner sides as shown in Fig. 7, with plate spring catches *e* which are secured thereto at *e*², and which are curved inwardly and upwardly, and provided at their upper ends with backwardly 70 directed hooks *e*³ adapted to engage corresponding hook members *e*⁴ secured to the top shutter members *b* as shown at *e*⁵, and the bottom shutter members are provided 75 above the point where the plate spring members *e* are secured thereto, with keepers *f* in which are mounted trippers *f*² adapted to bear on the inner sides of the upper end portions of the spring catches *e*, and to force said spring catches out of engagement 80 with the hook members *e*⁴, and said trippers *f* are provided with outwardly directed members *f*³ which pass through slots *e*⁶ in the spring catches *e*, and with which are connected cords *e*⁷ which are suspended 85 therefrom, and which pass downwardly and through keepers *e*⁸ secured to the lower portions of said lower shutter members *b*, and which are provided with rings *e*⁹ a pull 90 on which will disengage the hook members *e*³ from the hook members *e*⁴, and allow the bottom shutter members *b*² to be swung 95 outwardly as shown in Fig. 3, it being understood that the parts *e*³ and *e*⁴ aid in holding the shutter members *b*² in a closed 100 position as shown in Figs. 1 and 2, which operation is also aided by the hinge *d*.

In the position of the parts shown in Figs. 1 and 2 the shutters including both the top and bottom members thereof may 105 be swung outwardly in the manner of ordinary shutters in which operation said shutters swing on the hinges *c* and *d*, but when it is desired so to do the bottom portion or members *b*² of the shutters may be swung 110 outwardly and away from the window frame as shown in Fig. 3, by simply press-

ing thereon from the inner side thereof so as to disconnect the separate parts of the hinges d , and at the same time pulling on the cords e^7 so as to disengage the hook members e^3 and e^4 .

The top members b of the shutters are also provided with lock devices g for holding the shutters in a closed position said lock devices being shown in Figs. 1 and 4, and these lock devices consist of keepers g^2 secured to the top a^2 of the window frame, and other keepers g^3 secured to the top members b of the shutters, and in which are mounted spring operated bolts g^4 adapted to engage the keepers g^2 in the usual manner, and provided with pins g^5 which pass outwardly through slots g^6 in the keepers g^3 , and with which are connected cords g^7 which pass downwardly and inwardly through the top members b of the shutters as shown at g^8 , and which also extend downwardly and through keepers g^9 on the inner bottom portions of said shutters and which are provided with rings g^{10} a pull on which will release the locks g , and allow the shutters to be opened on the hinges c and d , and these lock devices will operate automatically to secure said shutters when they are swung into a closed position.

The top members b of the shutters are provided with transverse shutter slats i which are preferably stationary, but the bottom portions of the shutters d^2 are provided with transverse shutter slats j the upper edge portions of which are loosely connected with the side frames of said shutter members by means of staple shaped keepers j^2 on which the slats j are freely movable, and loosely connected with the slats j centrally and vertically thereof as shown in Fig. 1, and at j^3 in Fig. 6, are rods k with the upper ends of which are connected cords k^2 which are passed inwardly through the tops of the top shutter members b as shown at k^3 , and downwardly and inwardly of said shutter and out through the bottom of the bottom shutter members b^2 as shown at k^4 , and connected with the lower ends of the rods k and by means of the cords k^2 the slats j may be opened and closed as will be readily understood.

The outer edge portions of the shutter members b^2 are also provided with wings m which are hinged thereto at m^2 , and said wings m are provided with supplemental wing members n hinged thereto at n^2 , and the wing members m and n are triangular, in form, taken together, and adapted to be opened so as to close the side space between, the bottom shutter members b^2 , and the sides of the window frame, when said shutter members are swung outwardly on the hinges c^2 as shown in Fig. 3, or said wing members may be folded inwardly when the bottom shutter members are closed as shown in

Fig. 2. I also provide means for holding the bottom shutter members b^2 in the position shown in Fig. 3, consisting of rods o loosely connected with said shutter members at o^2 at one end, and the other ends of which are provided with hooks o^3 adapted to engage keepers o^4 secured to the window sill, or the bottom window frame member a^3 , and the rods o consist of separate parts o^5 and o^6 . The parts o^5 being provided with tubular socket members o^7 adapted to receive the parts o^6 , and the parts o^7 being provided with set screws o^8 whereby the part o^6 may be adjusted and secured therein as will be readily understood. The connection of the rods o with the shutter members at o^2 is a permanent connection, but the other ends of said rods may be disengaged from the keepers o^4 , and may be connected with corresponding keepers o^9 secured to the bottom shutter members and on the inner side therein as shown in Fig. 2, and this is the position that the rods o occupy when the shutters are closed. The top shutter members are also provided with anti-sagging hook devices p , which are secured thereto at p^2 , and as shown in Figs. 1 and 5. These hooks are adapted to engage plates p^3 secured to the top a^2 of the window frame when the shutters are closed so as to aid the hinges c of the top shutter members in supporting the bottom shutter members when the shutters are closed, and the operation of the hooks p is automatic as will be readily understood.

With this construction it will be seen that the shutters may be opened and closed in the manner of ordinary shutters whenever desired, or the bottom members b^2 thereof may be swung outwardly away from the bottom portion of the window frame whenever desired, and the spaces between the bottom shutter members when thus open may be closed by the side wing members $m-n$ and the shutter slats j may be opened or closed whenever it is necessary or desirable, and the shutters are thus made to operate in the manner of ordinary shutters or as awnings, and while I have shown and described the preferred form of my improvement it will be apparent that changes in, and modifications of the construction described may be made, within the scope of the appended claims, without departing from the spirit of my invention or sacrificing its advantages.

Having fully described my invention what I claim as new and desire to secure by Letters Patent is:—

1. The combination with a window frame, of a window shutter and awning comprising a pair of top sections each hinged at two points along their outer edges to the casing, and a pair of bottom members of the same width as said top members, and each hinged

- to the lower edge of one of said top members, each of said lower members being provided adjacent to its lower end with a hinge member and the window casing being provided 5 with hinge members to detachably engage the hinge members of said lower sections, the pivotal axis of each of said detachable hinges being in alinement with those of the two hinges of the adjacent upper section.
- 10 2. The combination with a window frame, of a window shutter and awning comprising a pair of top sections each hinged at two points along their outer edges to the casing, and a pair of bottom members of the same 15 width as said top members, and each hinged to the lower edge of one of said top members, each of said lower members being provided adjacent to its lower end with a hinge member and the window casing being provided 20 with hinge members to detachably engage the hinge members of said lower sections, the pivotal axis of each of said detachable hinges being in alinement with those of the two hinges of the adjacent 25 upper section, and locking means on each shutter located adjacent to the hinge connection between the top and bottom sections thereof for securing the top and bottom sections in the same plane, and preventing the 30 outward swinging of the bottom section.
3. The combination with a window frame, of a window shutter and awning comprising a pair of top sections each hinged at two points along their outer edges to the casing, 35 and a pair of bottom members of the same width as said top members, and each hinged to the lower edge of one of said top members, each of said lower members being provided adjacent to its lower end with a hinge member 40 and the window casing being provided with hinge members to detachably engage the hinge members of said lower sections, the pivotal axis of each of said detachable hinges being in alinement with those of the
- two hinges of the adjacent upper section, 45 spring locking devices for each shutter located adjacent to the hinge connection between the top and bottom sections thereof for securing the top and bottom sections in the same plane, movable releasing devices 50 for said locking devices and operative connections therefrom extending to points near the bottom of the shutter.
4. The combination with a window frame, of a window shutter and awning comprising a pair of top sections each hinged at two points along their outer edges to the casing, and a pair of bottom members of the same width as said top members, and each hinged to the lower edge of one of said top members, each of said lower members being provided adjacent to its lower end with a hinge member and the window casing being provided 60 with hinge members to detachably engage the hinge members of said lower sections, the pivotal axis of each of said detachable hinges being in alinement with those of the two hinges of the adjacent upper section, each of said shutters being provided adjacent to the hinge connections 65 between the sections thereof, with a spring hook secured to one section and adapted to engage a fixed part on the other section, a pivoted releasing device for each of said shutters having a part beneath the spring 70 hook for disengaging it from its stationary coacting part, and a connection from said releasing device depending therefrom to a point near the bottom of the shutter.
- In testimony that I claim the foregoing as 75 my invention I have signed my name in presence of the subscribing witnesses this 31st day of January 1912.

JOHN LOCKHART.
